UNITED STATES PATENT OFFICE

2,272,538

ELECTRIC CONNECTOR

Charles G. Wirth, Fair Oaks, Pa., assignor of forty per cent to Carl A. Nusskern, Pittsburgh, Pa.

Application August 30, 1939, Serial No. 292,727

6 Claims. (Cl. 173—332)

My invention relates to improvements in electrical connectors and more particularly to plugs of the appliance type which must be inserted into a closely fitting guard surrounding the plug jacks with which the plug is to be engaged.

One of the principal objects of my invention is to provide a plug of the above described character so constructed and arranged whereby the same may be readily and economically manufactured and assembled and which may be conveniently and quickly attached to electrical feed wires which are commonly of the flexible cord type.

Another object of my invention is to provide a connector construction which may be of a neat and attractive appearance and design without sacrifice of ruggedness, durability, efficiency, facility of use, or facility of wiring preparatory to use.

A further object of my invention is to provide a connector of the above described character equipped with means for facilitating removal of the connector from the plug jacks.

Other objects and advantages will be apparent from the following description, appended claims and annexed drawing.

Referring to the drawing wherein like reference characters designate like parts throughout the several views:

Figure 1 is a side elevation of my invention.

Figure 2 is a longitudinal section therethrough.

Figure 3 is a top plan view thereof.

Figures 4 and 5 are detail sectional views taken on the lines 4—4 and 5—5 respectively of Figure 1.

Figure 6 is a perspective view of the shroud.

In practicing my invention, as illustrated in the drawing, I provide a pair of molded insulating casing sections 10 and 11 of identical form and dimensions. The members or sections 10 and 11 are fashioned with flat inner faces which are normally adapted to lie against each other throughout the length thereof as clearly illustrated in Figures 4 and 5 of the drawing. Said inner faces are complementally recessed as at 12 to accommodate a pair of combined socket contact and wire terminal units 13, the latter being of the split socket type and provided at one end with binding screws 14 effecting connection with feed wires 15. The binding screws 14 are threaded within sockets formed in the section 11 whereby to secure said units 13 fixed thereto as clearly illustrated in Figure 4 of the drawing.

The jack engaging end of the sections 10 and

11 are formed with opposed pairs of apertures 16 defining openings communicating with the recesses 12 and through which the plug jacks of an appliance are received for insertion within the socket contact ends of the units 13. The opposite ends of the sections 10 and 11 receive thereon a bonnet 17 through which the wires 15 extend and which bonnet encloses and protects the binding screws 14. One end of the bonnet 17 is interiorly recessed to define a seat 18 accommodating the upper ends of the sections 10 and 11. The sides of the bonnet are formed with laterally disposed arcuate-shaped bosses 18' over which are extended the upper ends of bails 19, the lower ends being pivotally connected to the upper section of a shroud 20 embracing the sections 10 and 11 and securing the same in connected relation to form a unitary connector casing. The oppositely disposed ends 20 of the shroud 20 are slotted an appreciable distance towards the top to permit expansion in the lower section thereof. The upper faces of the bosses 18' at the jointure with the body proper of the bonnet 17 are recessed to provide seats 21 for receiving the upper ends of the bails 19 as clearly illustrated in Figures 1 and 2 whereby to preclude accidental displacement of the upper ends of the bails outwardly over said bosses.

From the foregoing it will be apparent that by displacing the upper ends of the bails 19 outwardly over the bosses 18 the shroud may be lowered and detached from the sections 10 and 11 and thus permit the bonnet 17 and the sections to be disassembled with respect to each other for connecting or disconnecting the wires 15 to the units 13. A reverse operation serves to effect assembling of the device and it is to be noted that the bosses 18 also constitute finger pieces whereby the device may be readily connected and disconnected from the plug jacks of an appliance.

It will be apparent, from the foregoing, that I have provided a simple and efficient connector or plug which may be readily disassembled for connecting the feed wires thereto and at the same time may be conveniently attached or detached from the appliance.

It is obvious that the invention is not confined to the herein described use therefor as it may be utilized for any purpose to which it is adaptable. It is therefore to be understood that the invention is not limited to the specific construction as illustrated and described, as the same is only illustrative of the principles of operation,

which are capable of extended application in advance forms, and that the invention comprehends all construction within the scope of the appended claims.

What I claim is:

1. A device of the character described, comprising, a casing having a pair of separable sections, a bonnet fitting said casing, a shroud surrounding said sections for securing the same in connected relation, and bails detachably connecting said shroud to said bonnet for maintaining the latter and said sections in connected relation.

2. A device of the character described, comprising, a casing having a pair of separable sections, a bonnet fitting said casing and provided with outwardly extending end portions, a shroud surrounding said sections for securing the latter in connected relation, and bails detachably connecting said shroud to said portions for maintaining said bonnet and said sections in connected relation.

3. A device of the character described, comprising a casing having a pair of separable sections, a bonnet resting upon the upper ends of the sections and extending around the side walls thereof, a shroud surrounding said sections and securing the same in their proper engaged position, and bails pivotally carried by the shroud and extending over the bonnet for maintaining the same and the sections in their assembled position.

4. A device of the character described, comprising a casing having a pair of separable sections with tapering outer walls, a bonnet resting on the upper ends of the sections, a tapering shroud surrounding said sections, and bails pivoted to the shroud and adapted to swing upwardly over the edges of the bonnet for maintaining the same and said sections in their assembled position.

5. A device of the character described, comprising a casing having a pair of separable sections, a bonnet fitting over said sections, a shroud removably surrounding the lower ends of the sections and having a limited upward movement, and bails pivotally carried by the shroud and adapted to swing over the bonnet for maintaining the same and the sections in their assembled position.

6. A device of the character described comprising a casing having a pair of separable sections, a bonnet fitting over said sections, ears carried by the ends of said bonnet, a shroud removably surrounding the lower ends of the sections and having a limited upward movement thereon, and bails pivotally carried by the shroud and adapted to swing upwardly at an angle over the ears on the bonnet for maintaining the same on the sections and holding the sections within the bonnet.

CHARLES G. WIRTH.
